UNITED STATES PATENT OFFICE.

GEORGE F. MAYER, OF CHICAGO, ILLINOIS.

LOCK.

1,421,522.

Specification of Letters Patent.

Patented July 4, 1922.

Application filed October 15, 1920. Serial No. 417,070.

To all whom it may concern:

Be it known that I, GEORGE F. MAYER, a citizen of the United States, and a resident of the city of Chicago, county of Cook, and 5 State of Illinois, have invented certain new and useful Improvements in Locks, of which the following is a specification.

My invention relates to locks of a type comprising a plurality of tumblers, each 10 of which is adapted to be actuated for effecting a locking operation and all of which may be moved out of locking relationship by operation in a certain predetermined sequence and order, and it is the principal 15 object of my invention to provide an improved construction and arrangement by reason of which an effective locking may be secured, while at the same time the mechanism may readily be manipulated by one 20 having the required information.

Other objects will appear hereinafter.

The invention consists in the combinations and arrangements of parts herein- 25 after described and claimed.

The invention will be best understood by reference to the accompanying drawings forming a part of this specification, and in which,

Fig. 1, is a front elevation of my im- 30 proved lock,

Fig. 2, a horizontal section taken through my improved lock near the top portion thereof, and showing the lock mounted in position on a door,

Fig. 3, a vertical section taken substan- 35 tially on line 3—3 of Fig. 2,

Fig. 4, a horizontal section taken substan- 40 tially on line 4—4 of Fig. 3,

Fig. 5, a vertical section taken substan- 45 tially on line 5—5 of Fig. 3 and showing, in dotted lines, a changed position of certain of the parts.

Fig. 6, a verticle section similar to Fig. 5, with the lower portion broken away, 45 and showing another changed position of certain of the parts,

Fig. 7, another view similar to Fig. 5, also partly broken away and showing still another changed position, and

Fig. 8, a detailed sectional view as taken on line 8—8 of Fig. 3, partly broken away, and showing diagrammatically an electric alarm system in connection with the lock.

Referring to the drawings, 15 indicates a

casing which is secured by angle bars 16 55 in a door 17 of any suitable type for closing a doorway between posts a fragmentary portion of one of which is shown in Fig. 2 and indicated by the numeral 18. Within the casing 15 there is mounted a frame-work 60 comprising side plates 19 and 20 and a transversely extending plate 21, as best shown in Fig. 4. The side plates 19 and 20 are connected at their forward ends to a heavy face plate 22, and are connected at 65 their rear ends to the rear face of the casing 15, as shown in Fig. 2. Mounted upon the upper edge of the plate 21 is a cross-bar 23, which is in the form of an angle bar, as is shown in Figs. 5 and 6, with ears 70 24 extending upwardly at its end portions. The upwardly directed rear edge of the plate of the bar 23 is in the form of a rack, as is shown in Fig. 2. A locking bolt 25 is slidably mounted upon the crossbar 23, 75 such bolt being slidably mounted between the rack portion of the bar 23 and the ears 24 of such bar, as is best shown in Fig. 2. An arm 26 extends forwardly from the locking bolt 25, being turned upwardly at 80 its forward end and provided with a plurality of teeth on its upper end, whereby it is adapted to be operated by a toothed wheel 27 which is revolubly mounted a short distance in the rear of the face plate 22 upon 85 a pin 28 which is provided at its forward end with a thumb nut 29. The locking bolt 25 is also provided with rack teeth upon its upper edge, as shown in Fig. 2, which teeth correspond in shape and spacing with 90 the teeth of the crossbar 23, the arrangement being such that a tumbler inserted in the space between the teeth of one bar is adapted also to engage the space between the teeth of the other bar for holding the parts 95 against longitudinal movement with respect to each other. The bolt 25 is provided at one end with a pin 30, which is movable longitudinally therewith, and which is adapted to be projected through an open- 100 ing 31 in the side of the casing 15 into contact with an auxiliary locking bolt 32, which, in turn, is adapted to be projected from the edge of the door into operative engagement with a suitable keeper 33 mounted in the 105 door post 18. A spring 34 is provided for retracting the bolt 32 when the pin 30 is withdrawn by the movement of the locking

bolt 25 toward the right in Fig. 2, through the medium of the thumb nut 29, as above described.

For locking the bolt 23 in either its projected or its retracted position, as above described, I have provided a plurality of tumblers 35, the forward ends of which are mounted in position upon a cross plate 36 above the edge of the plate 21, as is clearly shown in Figs. 5 and 6. The tumblers 35 are supported at their rear ends by means of vertically disposed levers 37, which are pivotally mounted by means of a cross rod 38 extending between the frame members 19 and 20, as is best shown in Figs. 3 and 5. As is clearly shown in Fig. 3, the upper end of each of the levers 37 is bifurcated so as to provide a suitable seat for the rear end portion of the tumbler 35. As is best shown in Fig. 2, each of the tumblers 35 is provided with shoulders near its rear end, whereby a forward movement of the upper end of the lever 37 serves to push the tumbler forwardly. As is best shown in Fig. 5, when the tumbler 35 is in its rearmost position, its lower edge rests upon the plate 36, serving to hold the tumbler out of engagement with the rack formed upon the locking bolt 25, but when the tumbler is moved forwardly, a notch 39 in the lower edge of the tumbler is brought into engagement with the plate 36, permitting the forward end of the tumbler to move into position between the teeth of the rack bar carried by the locking bolt. When the lever 37 is brought back to normal position after having produced a forward movement of the tumbler, as above described, the tumbler is prevented from returning with the lever by reason of the engagement of the notch 39 with the plate 36.

Means is provided for operating each of the levers 37 independently of the remaining levers, such means comprising a plurality of push bars 40 which extend through suitable openings in the face plate 22, as is clearly shown in Fig. 1. In the construction shown, twelve of the push bars 40 are provided, arranged in three tiers, as shown in Fig. 5, each tier comprising four push bars, as shown in Fig. 4. Each of the push bars 40 of the upper two tiers is provided with offset rear end portions 41 extending vertically so as to have a suitable connection with the lower end of one of the levers 37, as is best indicated in Figs. 3 and 5. By the use of the push bars 40, any one of the levers 37 can be given a rocking movement in counter-clockwise direction, as shown in Fig. 5, serving to cause a forward movement of the correspondingly positioned tumbler 35, unless such tumbler is already at the limit of its forward movement. Thus, any one of the tumblers 35 which is provided with the notch 39 in its lower face, may be moved forward into locking position independently

of the remaining tumblers. Springs 42 are mounted upon the push bars 40, bearing at their rear ends upon the plate 21 and at their forward ends having a bearing against suitable pins 43, whereby the push bars are adapted to return to normal position when released after having been pushed rearwardly.

Means is provided for retracting the tumblers 35 from locking position. This means comprises a rod 44 extending across the lock, in position to contact the lower edges of the tumblers 35 when in their forward locking position, as shown in Fig. 5. The rod 44 is mounted in slide bars 45 and 46, as is best shown in Fig. 4. These bars are slidably mounted between vertically extending ribs 47 and 48 formed on the inner faces of the side plates 19 and 20. Anti-friction rollers 49 are mounted on the bars 45 and 46 for providing a bearing for the bars between the plates 19 and 20. At their upper ends, the bars 45 and 46 are connected by a cross rod 50 by which motion is transmitted to the rod 44, as hereinafter described. The rod 50 in turn is moved by an arm 51 having a tapered forward end extending underneath said rod 50, being supported in position by a cross rod 52 at its forward end, and being pivotally connected at its rear end with a vertically disposed arm 53 mounted on one of the levers 37. As will be readily understood, when the lever 37 upon which the vertical arm 53 is mounted, is turned on its pivot by a backward push upon the appropriate push bar 40, the cross rod 50 is caused to rise by reason of the inclination of the contacting face of the arm 51, serving thus to raise the cross rod 44 and the various tumblers 35 which may be resting thereon, as the tumbler 35 shown in dotted lines in Fig. 5 is seen to be doing. It is thus seen that the several tumblers 35 are adapted to be moved forwardly into locking position by the use of the appropriate push bars 40, each tumbler being given this movement independently of the remaining tumblers, but that all of the tumblers 35 which may be standing in locking position are adapted to be raised out of locking position by the use of the push bar corresponding to the lever 37 upon which the arm 53 is mounted.

As will be appreciated, the arm 53 may be shifted from one to another of the levers 37, as may be desired, being removably mounted in position by the use of a screw 54 which is adapted to be inserted in any one of the screw-threaded openings 55 of the several levers 37 (see Fig. 3). As is shown in Fig. 2, the tumbler 35 is omitted from the lever 37 by which the arms 51 and 53 are carried. When the arms are shifted from one lever 37 to another, the tumblers 35 can be given a correspondingly changed arrangement. Upon an upward movement of the

tumblers 35 through the medium of the cross rod 44, the tumblers are prevented from rising at their rear ends by means of a cross rod 56 mounted in lugs 57 carried by the 5 side plates 19 and 20 in position directly above the tumblers, as is shown in Figs. 2 and 5.

Means is also provided for moving the tumblers 35 backwardly out of their locking position upon their upward movement. 10 This means comprises cams 58 formed on the upper faces of tumblers 35, as such tumblers are illustrated in Figs. 5 and 6. A cross rod 59 is movably mounted directly 15 above the cams 58 between lugs 60 formed on the side plates 19 and 20, coiled springs 61 being connected between the rod 59, and suitable portions of the framework, for holding the said rod 59 yieldingly downward. 20 When the tumblers 35 are raised at their forward ends, the cams 58 are brought into contact with the rod 59, serving to place the springs 61 under tension, such springs in turn serving to cause a backward movement 25 of the tumblers by reason of the inclination of the bearing faces of the cams 58. It is thus seen that by a backward movement of any one of the push bars 40, the lever 37 of which is provided with a tumbler 35, such 30 tumbler 35 is moved forward into locking position for holding the bolt 25 against movement in either direction, the lever being withdrawn backwardly by the action of the spring 42 when released. Upon a subsequent 35 backward movement of that one of the push bars 40, the lever 37 of which carries the arms 53 and 51, all of the tumblers 35 which have, previously thereto, been moved forward to their locking position, 40 will be retracted from locking position so as to permit a movement of the bolt 25, through the medium of the handle 29.

As is best shown in Fig. 7, a tumbler 62 is adapted to be mounted in position in lieu of 45 one or more of the tumblers 35. In the construction shown, the tumbler 62 is of precisely the same form as the tumbler 35 but is mounted in inverted position. As shown in said Fig. 7, the tumbler 62 rests upon the 50 cross bar 36, with its forward end in engagement with the rack formed upon the locking bolt 25. The forward end portion of the tumbler 62 is in the form of a cam, whereby, upon a forward movement of the tumbler 55 62, the end of the tumbler is carried upward out of engagement with the locking bolt 25, as is indicated in dotted lines in said Fig. 7. The tumbler 62 is provided with a cam 63 upon the upper face of the tumbler in the 60 position the tumbler occupies in Fig. 7, the cam corresponding to the cam 58 upon its opposite face, which is operative in the inverted position of the tumbler. The cam 63 operates upon the tumbler 62 for moving 65 the tumbler backward when raised at its

forward end in precisely the same manner as that already described in connection with the cam 58 upon the tumbler 35. The tumbler 62 is provided with a notch 64 on its lower face, in position directly above the 70 cross rod 44, the tumbler 62 accordingly being adapted to remain in locking position when the cross bar 44 is moved upwardly. In this way, the forward movement of the arms 51 and 53, carried by one of the levers 75 37, is effected, without causing a release of the tumbler 62. It will be appreciated, from an inspection of Fig. 7, that upon a backward movement of the push bar 40 connected with one of the levers 37 which is 80 provided at its upper end with a tumbler 62, such tumbler will be moved forward out of locking position, such movement being effected against the action of the springs 61, which springs will serve to move the tumbler 85 backward again into locking position when the actuated push bar 40 is released, and returned to normal position by its spring 42. Inasmuch as the tumbler 62 is merely one of the tumblers 35 in inverted 90 position, it will be appreciated that any one or more of the tumblers 35 may be inverted as desired, so as to obtain the alternative operation as above described.

With the tumblers 35 and 62 in position, 95 an operator knowing the proper method of unlocking the bolt 25, will push backwardly upon the push bar 40 corresponding with the lever 37 carrying the arms 53 and 51, and at the same time will push upon the appropriate push bar or push bars 40 corresponding 100 to the levers 37 which carry tumblers 62. In this way all of the tumblers 35 which may have previously been moved forward into locking position will be moved backwardly out of locking position through the action of the arm 51, and at the same time one or more tumblers 62 will be moved forwardly out of locking position, thus releasing the bolt 25 for operation by the thumb 110 piece 29. When an unauthorized attempt is made to open the lock, the backward movement of each of the push bars 40 corresponding with levers 37 provided with tumblers 35 will move an additional tumbler 35 115 into locking position, serving to make the device more secure rather than to have any tendency to release the bolt.

Means is provided for giving an alarm at any and all times when one of the push bars 120 40 is operated for releasing the lock. This means, in the construction shown, comprises a bar 65 slidably mounted between the side plates 19 and 20, as is best shown in Fig. 3. The bar 65 is to be made of metal which is 125 an effective conductor of electricity. The bar is mounted directly in the rear of the levers 37 at their lower end portions, so as to be moved backward into engagement with contacts 66 which are connected in circuit 130

with an electric bell 67, as is shown diagrammatically in Fig. 8. Spring means 68 is provided, serving normally to hold the bar 65 in its forward position out of engagement with the contacts 66.

Means is also provided for serving as a night lock, by the use of which operation of the lock by means of the push bars 40 can be prevented. This means comprises a screw 10 69 having a screw-threaded seat in the rear face of the casing 15 adjacent to the bar 65. By moving the screw 69 forward into engagement with the bar 65, which in turn is in contact with the levers 37, the levers are 15 held against a rocking movement, serving to prevent an operation of the lock by the use of the push bars.

Means is also provided for preventing an operator from opening the lock by pushing 20 all of the push bars 40 backward in unison. This means comprises a vertically extending bar 70, (see Fig. 5), which is provided with a hook 71 at its upper end which engages the cross bar 50, as is best shown in Figs. 25 3 and 5. The bar 70 is provided in its front face with a plurality of notches 72, which are in a position and of a shape to receive therein suitable portions of the push bars 40, the bar 70 being mounted in appropriate 30 position for this purpose. In the construction shown, the notches 72 are adapted to be engaged by shoulders 73 formed in the push bars 40, as is best shown in Fig. 4. When an attempt is made to press all of the 35 bars 40 backwardly, three of such bars are brought into engagement with the rod 70 serving to hold the rod 70 against upward movement, which in turn serves to hold the cross rod 50 against upward movement, thus preventing the bar 44 from acting to raise the tumblers 35. While I have shown in my drawings only one of the bars 70, it will be understood that additional bars of this type may be used if desired.

40 Means is provided for operating the tumblers for releasing the bolt 25 from the inner face of the casing 15 without the use of the push bars 40. This means comprises a yoke lever 74 mounted upon pivot pins 75 carried by the side plates 19 and 20, as is best shown in Fig. 4. The arms of the lever 74 are provided at their forward ends with a cross rod 76 which is mounted in position underlying the cams 58 or 63 of the tumblers 35 and 62, respectively. A spring 77 is connected with the lever 74 at its forward end, serving to hold the lever yieldingly in such position that the cross bar 76 shall press very lightly if at all upon the tumblers.

50 When lever 74 is depressed at its rear end, as is shown in Fig. 6, the cross rod 76 exerts an upward pressure upon the tumblers, serving to raise the tumblers out of locking position. The means for operating the lever 55 75 in this manner comprises an arm 78 ris-

ing from the cross bar of the yoke lever 74. Means is provided for depressing the arm 78 and for turning the pinion 27 for operating the locking bolt 25. This means comprises a pin 79 pivotally connected with the 70 toothed wheel 27 and extending backwardly therefrom, being provided with a lug 80 on its lower face which engages the upper end of the arm 78. The rear end of the pin 79 extends backwardly through a slot 81 in the 75 wall of the casing 15, being provided on its outer end with a thumb piece 82. By a downward movement of the thumb piece 82, through the medium of the lug 80 and the arm 78, the lever 74 is turned about its pivot pins 75 for raising the tumblers 35 and 62 by the action of the cross rod 76. While the tumblers 35 and 62 are held in raised position in this way, the thumb piece 82 can be turned, serving in turn to rotate the toothed 85 wheel 27 for moving the bolt 25 longitudinally either into or out of position for projecting the auxiliary bolt 32.

While I have illustrated and described the preferred form of construction for carrying 90 my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. A lock comprising a slidably mounted bolt; manually operable means for moving said bolt; a longitudinally movable tumbler mounted adjacent to said bolt adapted, 105 by a movement across the bolt, to lock the bolt against movement; means for moving the tumbler into locking position; and similarly actuating independently acting means for rocking the tumbler out of locking position, substantially as described.

2. A lock comprising a slidably mounted bolt; manually operable means for moving said bolt; a longitudinally movable tumbler mounted adjacent to said bolt adapted, by 115 a movement across the bolt, to lock the bolt against movement; a push bar adapted, by a movement in one direction, to move the tumbler into locking position; and a second independently acting push bar adapted, by 120 a movement in the same direction, to rock the tumbler out of locking position, substantially as described.

3. A lock comprising a slidably mounted bolt; manually operable means for moving 125 said bolt; a longitudinally movable tumbler mounted adjacent to said bolt adapted, by a movement toward the bolt, to lock the bolt against movement; a push bar adapted, by a movement in one direction, to move the 130

- tumbler into locking position; a spring for returning said push bar to normal position, the arrangement being such that upon the return of the push bar the tumbler remains 5 in locking position; and a second similarly actuated independently acting push bar adapted, by an operative movement to rock the tumbler out of locking position, substantially as described.

10 4. A lock comprising a slidably mounted bolt; manually operable means for moving said bolt; a longitudinally movable tumbler mounted adjacent to said bolt adapted, by a movement toward the bolt, to lock the bolt 15 against movement; means for moving the tumbler into position to lock said bolt; latching means for holding said tumbler against retraction from locking position; and spring actuated means for retracting 20 said tumbler when released from said latching means, substantially as described.

15 5. A lock comprising a slidably mounted bolt; manually operable means for moving said bolt; a longitudinally movable tumbler mounted adjacent to said bolt, adapted, by a movement across the bolt, to lock the bolt 25 against movement; means for moving the tumbler into position to lock said bolt; means adapted upon rocking movement of 30 said tumbler to cause a retraction thereof; latching means for holding said tumbler against retraction until rocked; and means for rocking said tumbler for releasing it for retraction, substantially as described.

35 6. A lock comprising a slidably mounted bolt; manually operable means for moving said bolt; a longitudinally movable tumbler mounted adjacent to said bolt adapted, by a movement toward the bolt, to lock the bolt 40 against movement; means for moving the tumbler into position to lock said bolt; a spring adapted upon rocking movement of 45 said tumbler to cause a retraction thereof from locking position; latching means for holding said tumbler against retraction until rocked; and means for rocking said tumbler for releasing it for retraction, substantially as described.

50 7. A lock comprising a slidably mounted bolt; manually operable means for moving said bolt; a longitudinally movable tumbler mounted adjacent to said bolt and adapted, by a movement toward the bolt, to lock the bolt 55 against movement; a push bar adapted, by a movement in one direction, to move the tumbler into position to lock said bolt; a spring adapted, upon rocking movement of 60 said tumbler, to cause a retraction thereof from locking position; latching means for holding said tumbler against retraction until rocked; and means operable independently of said push bar for rocking said tumbler for releasing it for retraction, substantially as described.

65 8. A lock comprising a slidably mounted bolt; manually operable means for moving said bolt; a longitudinally movable tumbler mounted adjacent to said bolt and adapted, by a movement toward the bolt, to lock the bolt 70 against movement; means for moving the tumbler into position to lock said bolt; a spring adapted, upon upward movement of said tumbler, to cause a retraction thereof from locking position; means for holding said tumbler against retraction until moved 75 backwardly; and means operable independently of said first named tumbler-moving means for raising said tumbler for releasing it for retraction, substantially as described.

9. A lock comprising a slidably mounted bolt; manually operable means for moving said bolt; a longitudinally movable tumbler mounted adjacent to said bolt and adapted, by a movement toward the bolt, to lock the bolt 80 against movement; a push bar adapted, by a movement in one direction, to move the tumbler into position to lock said bolt; a spring adapted, upon upward movement of said tumbler, to cause a retraction thereof from locking position; means for holding said tumbler against retraction until moved upwardly; and a second push bar operable independently of 85 said first named push bar for raising said tumbler for releasing it for retraction, substantially as described.

10. A lock comprising a slidably mounted bolt; manually operable means for moving said bolt; a longitudinally movable tumbler mounted adjacent to said bolt and adapted, by a movement across the bolt, to lock the bolt 90 against movement; means for moving the tumbler into locking position; and cam-operated means for rocking the tumbler so that same can be moved out of locking position, substantially as described.

11. A lock comprising a slidably mounted bolt; manually operable means for moving said bolt; a longitudinally movable tumbler mounted adjacent to said bolt and adapted, by a movement toward the bolt, to lock the bolt 95 against movement; means for moving the tumbler into position to lock said bolt; a spring adapted, upon a rocking movement of said tumbler, to cause a retraction thereof from locking position; latching means for holding said tumbler against retraction until rocked upwardly; and cam-operated means for rocking said tumbler so that same 100 can be retracted substantially as described.

12. A lock comprising a slidably mounted bolt; manually operable means for moving said bolt; a longitudinally movable tumbler mounted adjacent to said bolt and adapted, by a movement toward the bolt, to lock the bolt 105 against movement; a push bar adapted, by a movement in one direction, to move the tumbler into position to lock said bolt; a spring adapted, upon upward movement of said tumbler, to cause a retraction thereof from locking position.

of from locking position; means for holding said tumbler against retraction until moved upwardly; and cam-operated means operable independently of said push bar for 5 raising said tumbler for releasing it for retraction, substantially as described.

13. A lock comprising a slidably mounted bolt; manually operable means for moving said bolt; a longitudinally movable tumbler 10 mounted adjacent to said bolt and adapted, by a movement toward the bolt, to lock the bolt against movement; a push bar adapted, by a movement in one direction, to move the tumbler into position to lock said bolt; 15 a spring adapted, upon upward movement of said tumbler, to cause a retraction thereof from locking position; means for holding said tumbler against retraction until moved upwardly; a second push bar operable independently of said first named push bar; a cam adapted to be moved by said second push bar; and means operated by said cam for raising said tumbler for releasing it for retraction, substantially as described.

25 14. A lock comprising a slidably mounted bolt; manually operable means for moving said bolt; notches in said bolt; a longitudinally movable tumbler mounted adjacent to said bolt adapted to be moved into position 30 to engage said notches in the bolt for holding the bolt either in locking position or in retracted position; means for moving the tumbler into locking position; and independently acting means for moving the 35 tumbler out of locking position, substantially as described.

15. A lock comprising a slidably mounted bolt; manually operable means for moving said bolt; a plurality of longitudinally movable tumblers mounted adjacent to said bolt, any one of which is adapted to be moved into position to lock said bolt against movement; and means for each of said tumblers for moving a tumbler into locking position 40 independently of the remaining tumblers; and cam operated means for moving all of said tumblers in unison out of locking position, substantially as described.

16. A lock comprising a slidably mounted bolt; manually operable means for moving said bolt; a plurality of longitudinally movable tumblers mounted adjacent to said bolt, any one of which is adapted to be moved into position to lock said bolt against movement; a push bar for each of said tumblers for moving a tumbler into locking position 55 independently of the remaining tumblers; and a similar additional push bar operable independently of said first named push bars 60 and having cam means for moving all of said tumblers in unison out of locking position, substantially as described.

17. A lock comprising a slidably mounted bolt; manually operable means for moving said bolt; a plurality of longitudinally mov-

able tumblers mounted adjacent to said bolt, any one of which is adapted to be moved into position to lock said bolt against movement; means for each of said tumblers for moving a tumbler into locking position independently of the remaining tumblers; 70 cams on said tumblers adapted, upon upward movement of the tumblers, to move the tumblers out of locking position; and means acting independently of said first named 75 tumbler-moving means for raising all of said tumblers in unison for moving them out of locking position, substantially as described.

18. A lock comprising a slidably mounted bolt; manually operable means for moving said bolt; a longitudinally movable tumbler having a cam mounted adjacent to said bolt adapted, when in normal position, to lock said bolt against movement, but adapted, when moved toward said bolt, to ride out of locking position; and means for moving said tumbler toward said bolt, substantially as described.

19. A lock comprising a slidably mounted bolt; manually operable means for moving said bolt; a longitudinally movable tumbler having a cam mounted adjacent to said bolt adapted, when in normal position, to lock said bolt against movement, but adapted, 95 when moved toward said bolt, to ride out of locking position; means for moving said tumbler toward said bolt; and other automatically acting friction means for returning said tumbler to locking position, substantially as described.

20. A lock comprising a slidably mounted bolt; manually operable means for moving said bolt; a longitudinally movable tumbler having a cam mounted adjacent to said bolt 105 adapted, when in normal position, to lock said bolt against movement, but adapted, when moved towards said bolt, to ride out of locking position; means for moving said tumbler toward said bolt; and spring operated frictionally engaging means for returning said tumbler to locking position, 110 substantially as described.

21. A lock comprising a slidably mounted bolt; manually operable means for moving said bolt; a longitudinally movable tumbler having a cam mounted adjacent to said bolt adapted, when in normal position, to lock said bolt against movement but adapted, when moved toward said bolt, to ride out of locking position; a second longitudinally movable tumbler mounted adjacent to said bolt adapted, by a movement across the bolt, to lock the bolt against movement; means for moving either of the tumblers toward said bolt independently of the other tumbler; and automatically acting friction means for returning said first named tumbler to locking position, substantially as described.

22. A lock comprising a slidably mounted

bolt; manually operable means for moving said bolt; a longitudinally movable tumbler having a cam mounted adjacent to said bolt adapted, when in normal position, to lock 5 said bolt against movement, but adapted, when moved toward said bolt, to ride out of locking position; a second longitudinally movable tumbler mounted adjacent to said bolt, adapted, by a movement toward the

10 bolt, to lock the bolt against movement; means for moving either of the tumblers toward said bolt independently of the other tumbler; latching means for holding said second tumbler against retraction from locking 15 position; and automatically acting means for returning said first named tumbler to locking position, substantially as described.

23. A lock comprising a slidably mounted bolt; manually operable means for moving 20 said bolt; a longitudinally movable tumbler having a cam mounted adjacent to said bolt adapted, when in normal position, to lock said bolt against movement, but adapted, when moved toward said bolt, to ride out of locking 25 position; a second longitudinally movable tumbler mounted adjacent to said bolt adapted, by a movement toward the bolt, to lock the bolt against movement; means for moving either of the tumblers 30 toward said bolt independently of the other tumbler; automatically acting means for returning said first named tumbler to locking position; latching means for holding said second tumbler against retraction from locking 35 position; other means adapted, upon upward movement of said second tumbler, to cause a retraction thereof from locking position; and means for raising said second tumbler, substantially as described.

40 24. A lock comprising a slidably mounted bolt; manually operable means for moving said bolt; a plurality of longitudinally movable tumblers mounted adjacent to said bolt, some having cams thereon, a plurality of 45 which tumblers are adapted, by a movement toward the bolt, to lock the bolt against movement, and the remainder of which tumblers having cams are adapted, when in normal position, to lock the bolt against movement, but are adapted, when moved toward 50 said bolt, to move out of locking position; independently operable means for each of said tumblers for moving the tumbler toward the bolt; automatically operating 55 means for retracting the tumblers which are moved out of locking position by movement toward the bolt; and other cam means for moving out of locking position in unison the tumblers which are adapted to lock upon 60 movement toward the bolt, substantially as described.

25. A lock comprising a slidably mounted bolt; manually operable means for moving said bolt; a tumbler adapted, by a movement 65 toward the bolt when in one position,

to lock the bolt against movement, and having cam means adapted, when in reversed position, to lock the bolt against movement when in retracted position and to ride out of locking position when moved toward the 70 bolt; and means for moving said tumbler in either position toward said bolt, substantially as described.

26. A lock comprising a slidably mounted bolt; manually operable means for moving 75 said bolt; a tumbler reversibly mounted in position adjacent to said bolt adapted, upon a movement toward the bolt when in one position, to move downwardly into locking engagement with the bolt for holding the 80 bolt against movement, and having cam means adapted, when in reversed position, to lock the bolt against movement when in retracted position and to ride upwardly out of locking position when moved toward the 85 bolt; and means for moving said tumbler in either position toward said bolt, substantially as described.

27. A lock comprising a slidably mounted bolt; manually operable means for moving 90 said bolt; a longitudinally movable tumbler mounted adjacent to said bolt adapted, when in normal position, to lock said bolt against movement; a cam on said tumbler adapted, upon a movement of the tumbler 95 toward the bolt, to raise the tumbler out of engagement with the bolt; and means for moving said tumbler toward said bolt, substantially as described.

28. A lock comprising a slidably mounted 100 bolt; manually operable means for moving said bolt; a longitudinally movable tumbler mounted adjacent to said bolt adapted, when in normal position, to lock said bolt against movement; a cam on said tumbler adapted, 105 upon a movement of the tumbler toward the bolt, to raise the tumbler out of engagement with the bolt; means for moving said tumbler toward said bolt; a second cam on said tumbler; and a spring pressed part 110 adapted to be displaced by said cam against the action of the spring upon the movement of the tumbler toward the bolt for returning the tumbler to locking position, substantially as described. 115

29. A lock comprising a slidably mounted bolt; a rack bar connected therewith; a supporting member adjacent said rack bar; a plurality of movable tumblers in inoperative position resting on said supporting 120 member and adapted, upon a movement toward the rack bar, to drop into engagement therewith for locking the rack bar against movement; and means for moving said tumblers into and out of locking position, substantially as described.

30. A lock comprising a slidably mounted bolt; a rack bar connected therewith, a supporting member adjacent said rack bar; a plurality of movable tumblers in inoper- 130

ative position resting on said supporting member and adapted, upon a movement toward the rack bar, to drop into engagement therewith for locking the rack bar against movement; means for moving said tumblers independently of each other toward said rack bar; and other means for moving said tumblers in unison out of locking position, substantially as described.

10 31. A lock comprising a slidably mounted bolt, a rack bar connected therewith; a plurality of movable tumblers adapted, upon a movement toward the rack bar, to drop into engagement therewith for locking the 15 rack bar against movement; means for moving said tumblers independently of each other toward said rack bar; other means for moving said tumblers in unison out of locking position; an additional tumbler 20 adapted, when at the limit of its motion away from the rack bar, to lock the bolt against movement and adapted, upon a movement toward the rack bar, to move upward out of engagement therewith; and 25 means for moving said last named tumbler independently of the remaining tumblers, substantially as described.

32. A lock comprising a slidably mounted bolt; a plurality of tumblers for locking said 30 bolt against movement; means for operating said tumblers for locking and unlocking said bolt; and means for holding said tumbler-operating means against movement, serving as a double lock, substantially as 35 described.

33. A lock comprising a slidably mounted bolt; a plurality of tumblers for locking said bolt against movement; a plurality of levers for moving said tumblers; and a bar 40 adapted to be held in position to prevent the swinging of said levers for moving the tumblers, substantially as described.

34. A lock comprising a slidably mounted bolt; a plurality of tumblers for locking 45 said bolt against movement; a lever for each of said tumblers for operating it independently of the remaining tumblers; an arm adapted to be mounted on any one of said levers; and means actuated by said 50 arm for moving said tumblers in unison out of locking position, substantially as described.

35. A lock comprising a slidably mounted bolt; a plurality of tumblers for locking 55 said bolt against movement; a lever for each of said tumblers for operating it independently of the remaining tumblers; an arm adapted to be mounted on any one of said levers; a cross bar extending underneath 60 said tumblers; and means connected with said cross bar and co-operating with said arm for moving the tumblers out of locking position, substantially as described.

36. A lock comprising a slidably mounted bolt; a plurality of tumblers for locking 65

said bolt against movement and adapted, by upward movement, to release the bolt; a lever for each of said tumblers for moving it into locking position independently of the remaining tumblers; and means extending beneath said tumblers acting independently of said levers for raising the tumblers in unison out of locking position, substantially as described.

37. A lock comprising a slidably mounted bolt; a plurality of tumblers for locking said bolt against movement and adapted, by upward movement, to release the bolt; a lever for each of said tumblers for moving it into locking position independently of the remaining tumblers; a pair of slide bars mounted in vertical position on opposite sides of the bank of tumblers; a cross bar connecting said slide bars rigidly together and positioned directly below said tumblers; and means for moving said cross bar upwardly for raising said tumblers out of locking position, substantially as described.

38. A lock comprising a slidably mounted bolt; a plurality of tumblers for locking 90 said bolt against movement and adapted, by upward movement, to release the bolt; a lever for each of said tumblers for moving it into locking position independently of the remaining tumblers; a pair of slide bars 95 mounted in vertical position on opposite sides of the bank of tumblers; a cross bar connecting said slide bars rigidly together and positioned directly below said tumblers; a second cross bar extending between said slide bars; and a cam arm movable underneath said second cross bar for moving it upwardly for raising said tumblers out of locking position, substantially as described.

39. A lock comprising a frame; a bolt 105 slidably mounted therein; a plurality of tumblers mounted on said frame for locking said bolt against movement and adapted, by upward movement, to release the bolt; a lever for each of said tumblers for moving it into locking position independently of the remaining tumblers; a pair of slide bars mounted in vertical position on opposite sides of the bank of tumblers; a cross bar connecting said slide bars rigidly together 110 and positioned directly below said tumblers; anti-friction rollers interposed between said slide bars and said frame; and means for moving said cross bar upwardly for raising said tumblers out of locking position, substantially as described.

40. A lock comprising a frame; a bolt 115 slidably mounted therein; a plurality of tumblers mounted on said frame for locking said bolt against movement and adapted, by upward movement, to release the bolt; a lever for each of said tumblers for moving it into locking position independently of the remaining tumblers; a pair of slide bars 120 mounted in vertical position on opposite

- sides of the bank of tumblers; a cross bar connecting said slide bars rigidly together and positioned directly below said tumblers; an additional lever adjacent to said first 5 named levers; a cam arm pivotally mounted on said second named lever and extending forwardly therefrom; a support on said frame for the forward end portion of said pivoted cam arm; and a second cross bar 10 extending between said slide bars and adapted to be engaged by said cam arm for moving the first named cross bar upwardly for raising said tumblers out of locking position, substantially as described.
- 15 41. A lock comprising a slidably mounted bolt; a plurality of tumblers for locking said bolt against movement and adapted, by upward movement, to release the bolt; means for operating said tumblers; and means ex- 20 tending beneath said tumblers operable from the rear face of the lock for raising said tumblers independently of the first named tumbler operating means, substantially as described.
- 25 42. A lock comprising a slidably mounted bolt; a plurality of tumblers for locking said bolt against movement and adapted, by upward movement, to release the bolt; means for operating said tumblers; a cross bar ex- 30 tending underneath said tumblers adapted, by an upward movement, to raise the tumblers out of locking position; and means operable from the rear face of the lock for moving said cross bar upwardly and then 35 moving the bolt into or out of locking position, substantially as described.
43. A lock comprising a slidably mounted bolt; a pinion by rotation of which said bolt is moved into and out of locking position; a 40 plurality of tumblers for locking said bolt against movement and adapted, by upward movement, to release the bolt; means for operating said tumblers; a cross bar extending underneath said tumblers adapted, by an up- 45 ward movement, to raise the tumblers out of locking position; a pin connected with said pinion but extending rearwardly therefrom for turning said pinion; and means actuated by a downward swinging of said pin for 50 moving said crossbar upwardly for moving the tumblers out of locking position, substantially as described.
44. A lock comprising a slidably mounted bolt; a plurality of tumblers for locking said bolt against movement; a push bar for each 55 of said tumblers for operating it; means actuated independently of said push bars for moving the tumblers out of locking position; and means serving, while one of said push bars is held at the limit of its operative 60 stroke, to prevent operation of said second named tumbler-moving means, substantially as described.
45. A lock comprising a slidably mounted bolt; a plurality of tumblers for locking said bolt against movement; a push bar for each of said tumblers for operating it; upwardly movable means acting independently of said push bars for moving the tumblers in unison out of locking position; and means serving, 70 while one of said push bars is held at the limit of its operative stroke, to prevent upward movement of said second named tumbler-moving means, substantially as described. 75
46. A lock comprising a slidably mounted bolt; a plurality of tumblers for locking said bolt against movement; a push bar for each of said tumblers for operating it; a cross bar underlying said tumblers and adapted, by 80 an upward movement, to move said tumblers in unison out of locking position; and a vertically disposed member adapted to move upwardly with said cross bar and provided with a notch adapted, by engagement with 85 one of said push bars, to prevent upward movement of the member when the push bar is in its rearmost position, substantially as described.
47. A lock comprising a slidably mounted bolt; a plurality of tumblers for locking said bolt against movement; a push bar for each of said tumblers for operating it; a cross bar underlying said tumblers and adapted, by 90 an upward movement, to move said tumblers in unison out of locking position; and a hooked member adapted to be removably inserted in position adjacent to one of said push bars with its hooked portion in engagement with said cross bar, said member being 95 provided with a notch adapted to be engaged by one of said push bars when moved to its rearmost position for preventing upward movement of the cross bar, substantially as described. 100
- 105 In testimony whereof I have signed my name to this specification in the presence of two subscribing witnesses.
